(57) **CLAIM**

The ornamental design for a stun gun, as shown and described.

DESCRIPTION

FIG. 1 is a front perspective view of a stun gun.

FIG. 2 is a left side elevation view of the stun gun of FIG. 1.

FIG. 3 is a right side elevation view from the stun gun of FIG. 1.

FIG. 4 is a top plan view of the stun gun of FIG. 1.

FIG. 5 is a bottom plan view of the stun gun of FIG. 1.

FIG. 6 is a front elevation view of the stun gun of FIG. 1; and,

FIG. 7 is a rear elevation view of the stun gun of FIG. 1. The broken lines shown in the drawings are included for the purpose of illustrating portions of the stun gun that form no part of the claimed design.
